UNITED STATES PATENT OFFICE.

WILLIAM J. REAGAN, OF LYNN, MASSACHUSETTS.

FRENCH CORD BINDER.

Application filed August 5, 1927. Serial No. 210,972.

My invention relates to so-called French cord binders, or attachments for French cord binding machines. It has for its purposes, to provide a new, novel, and improved means of attaching leather or fabric binding, gummed or otherwise, to the edge of a shoe or other material, and particularly the type of binding known as "Parco", to facilitate the holding, passing and control of the binding prior to the actual stitching process; to provide an attachment adjustable to various widths of binding; to provide a device which will attach the binding to an edge without shrinking, contracting or changing the dimensions of the material to which it is secured or the binding itself; to provide a new and improved presser means adaptable to function in combination with the binding attachment; and to provide the various other advantages and results disclosed from the following specification.

I accomplish the objects of my invention as shown in the accompanying drawings in which Figure 1 shows a side view of my assembled device in operating position as used with the foot of a sewing machine adaptable for French cord binding. Figure 2 shows a diagonal top view of my attachment or binding guide disengaged from the sewing machine foot shown in Figure 1. Figure 3 shows a side view of my binding guide likewise disengaged from the sewing machine foot shown in Figure 1. Figure 4 shows an enlarged sectional view of my attachment on the line X—X in Figure 3. Figure 5 shows the adjustment blade. Figure 6 shows a front view of my attachment.

Referring again to Figure 1, A shows the foot bar of a sewing machine of the type adaptable for French cord binding. B shows the foot fixed to the lower end of the bar A. C shows the adjustment screw by means of which the foot A is secured to the bar A. D shows the needle bar. E shows the needle positioned in the lower end of the bar D. F shows the body portion of my device. G shows the arm by which the device is secured to the machine by the screw H. I shows that part of the guide portion of my device next to the machine foot. J shows that part of the guide portion of my device away from the machine foot. K shows the adjusting member lying between the parts I and J. L shows the set screw

by which the adjusting member K is locked in position between the parts I and J. M shows the binding in position for feeding into my device. 60

Referring again to Figure 4, the sides I and J are shown to be U-shaped, forming an opening, through which in operation the binding passes. Referring again to Figure 5, K² shows the slot (in the adjusting member K) adaptable to fit about the screw L in adjusting the length of the opening N to fit various widths of bindings. The member K on its side K³ is made to extend from the top to the bottom of the opening N to better guide the binding as it passes through the opening N. The end K⁴ acts as a handle for convenience in making the adjustments. 65 70

Similar letters of reference refer to similar parts throughout the various views. 75

In operation the end of the binding M after passing through the opening N, is positioned at the starting point on the material to be bound beneath the needle E. The normal pull of the machine feed then draws the binding from the reel as the material to be bound passes under the needle. 80

I do not desire to confine myself to the specific details of construction herein shown 85 but claim all such equivalents and variations as fall within the scope of the appended claim.

Having thus described my invention I claim as new and desire to secure by Letters Patent of the United States of America: 90

An attachment for sewing machines, comprising a bracket for mounting on the foot of a sewing machine, a part integral 95 with and extending at an angle to the body of the bracket and having spaced apart relatively parallel portions forming a U-shaped, channeled construction in cross-section between which binding material is 100 guided to the needle of the machine, and a filler member between the portions to adjust the width of the channel receiving the binding, said member being slotted to receive a holding screw for fixing it in adjusted position, and a handle portion integral with the filler member for manipulating the same. 105

In testimony whereof I affix my signature.

WILLIAM J. REAGAN.
